UNITED STATES PATENT OFFICE.

ROBERT H. HAWTHORNE, OF NEW YORK, N. Y.

SEWING-MACHINE.

SPECIFICATION forming part of Letters Patent No. 312,467, dated February 17, 1885.

Application filed February 6, 1884. (No model.)

To all whom it may concern:

Be it known that I, ROBERT H. HAWTHORNE, of New York, in the county of New York and State of New York, have invented a certain 5 new and useful Improvement in Sewing-Machines, of which the following is a specification.

I will first describe a sewing-machine embodying my improvement, and then point out 10 in the claims the various features of the improvement.

In the accompanying drawings, Figure 1 is 15 a plan of a machine embodying my improvement. Fig. 2 is a partly-sectional elevation of the same, taken at the plane of the dotted line $x\ x$, Fig. 1. Fig. 3 is a partly-sectional elevation of the same, taken at the plane of the dotted line $y\ y$, Fig. 1. Fig. 4 is a plan or top view of the bed-plate, a detachable 20 section with which it is provided being removed. Fig. 5 is a vertical section taken on the plane of the dotted line $z\ z$, Fig. 4. Fig. 6 is a sectional elevation of the machine, taken at the plane of the dotted line $v\ v$, Fig. 25 1; and Fig. 7 is a perspective view of the feeding device detached, and having a portion broken away.

A designates the needle-bar of the machine. The needle B may be secured to the lower end 30 of the needle-bar in the ordinary or any other suitable manner. The needle-bar is shown as secured by a screw, a , in a socket, b , provided for its reception in the end of a slider-bar, C. The slider-bar has a flat shank fitting in a vertical guideway provided for it in a standard, D, erected on the bed-plate E of the machine. The guideway of the standard D comprises plates which are secured in place by screws, and hence may be removed at 35 pleasure. The upper end of the slider-bar C is bent over considerably beyond the standard D, in order that the needle-bar A may be located at some distance from the standard. The advantage of this is to afford room for 40 the work.

On the slider-bar C is a stud, c , which has connected to it a pitman-rod, F. The lower end of the pitman-rod F fits an eccentric, G' , affixed to a main or driving shaft G. In 45 lieu of the eccentric, a crank or cam may be used. The shaft G is journaled in the bed-plate, and has arranged upon it, close to the

eccentric G' , a belt-pulley, G^2 . A belt applied to the pulley G^2 may transmit motion to the shaft G. On the shaft G is also shown 55 a wheel or pulley, G^3 . As the shaft G rotates, the slider-bar C is reciprocated up and down and carries the needle-bar with it. The means described for reciprocating the needle-bar are very simple, are very direct in action, 60 and are not liable to get out of order.

H designates a presser-bar supported in bearings in an arm, D', extending from the upper part of the standard D. A tongue, d , extending from the presser-bar and fitting in 65 a slot or recess in the upper bearing of the arm D', prevents the presser-bar from turning. A spiral spring, H', surrounding the presser-bar between its upper bearing and a pin projecting from it, impels the presser-bar 70 downward. The presser-bar may be raised by manipulating a cam-lever, H', which is pivoted to it by a screw, e, and impinges against the top of its upper bearing.

I is a tension device, which may be of ordinary or any other appropriate construction.

J designates a spool-holder, consisting, as here shown, of a metal rod extending from the standard D.

On the inner end of the shaft G, in line 80 with the needle, is a rotary looping-hook, G ^{4} .

I will now describe the feed mechanism.

K designates a metal bar hung at one end on a stationary support, and having a reciprocating and a swinging movement. It has on the 85 top, at the rearward end—or, in other words, at the end which is the nearer to the shaft G—a feed-piece, s. The support on which this bar K is hung consists of a metal screw or pin, K', fastened to a rib, E', under the bed-plate 90 E, and having upon it a shoe, K ^{2} . The bed-plate E, the standard D, and the rib E' may be cast together. The shoe K ^{2} fits snugly between the upper and lower sides of a slot, f, with which the bar K is provided. The slot 95 f of the bar K is longer than the shoe K ^{2} ; hence the said bar may be slid lengthwise over the said shoe. At the front of the slot f is a packing, f', of leather or other suitable material. This is used to prevent any noise when 100 the bar K is limited in its rearward movement, or movement toward the shaft G, by the shoe. A spring, K ^{3} , is arranged in a socket in the bar K, to the rear of the shoe K ^{2} , and at the front

or inner end it impinges against the rearward side of the shoe; hence it always tends to move the bar backward or toward the shaft G.

K⁴ designates a rod which at one end fits a 5 crank or eccentric, G⁵, with which the shaft G is provided, and at the other end fits in a socket in the bar K. The outer portion of this socket is internally screw-threaded, and has inserted in it a screw, K⁶. Preferably this screw 10 is split so as to form two resilient portions, which, by their pressure in the socket, produce such friction that the screw cannot be accidentally turned in the socket. Between the rod K⁴ and the screw K⁶ there are preferably 15 interposed a washer or plug, g, of leather or other soft material, and a thin metal disk, h. The washer or plug is used simply to avoid the noise which otherwise would result from the contact of the rod K⁴ with the screw K⁶. 20 As the crank reciprocates the rod K⁴ it alternately causes it to press toward the screw K and then move in the reverse direction. When the rod moves in the direction last referred to, the spring K³ causes the bar K to 25 move in the same direction as far as it is capable of moving. By adjusting the screw K⁶ into the socket so far that when the bar is moved into its extreme rearward position, or as near to the shaft G as it can go, there will be no 30 space between the screw, the disk h, the plug g, and the rod K⁴; the bar will be moved back and forth a distance equal to the full throw of the crank or eccentric G⁵, and a very long stitch will be made in the work. When, 35 however, the screw K⁶ is adjusted more or less outward, the rod K⁴ will be capable of moving some distance before exerting any force against the screw; hence there will be more or less lost motion between the rod and the screw and the 40 bar K will be moved a shorter distance. The stitch produced will thus be shortened. By adjusting the screw the stitch may be varied at pleasure.

The bar K is always moved backward or toward the shaft G by means of the spring K³ to the same position, because even when the extent of its movement is varied the variation is made in the movement which is derived from the crank in the opposite direction. It 45 follows, therefore, that the said bar K is always moved up into the same position relatively to the needle.

The extent of the feed movement of the feed-bar, as herein shown, depends upon the 50 length of the rod K⁴, the thickness of the washer or plug g and disk h, the position of the screw K⁶, and the length of the slot f rearward of the packing f', as compared with the distance between the forward and rear

sides of the shoe K². The length of space 60 between the packing f' and the rearward end of the slot f, as compared with the distance between the forward and rear sides of the shoe K², must of course be at least as great as the extreme length of throw which the rod K⁴ is 65 capable of imparting to the feed-bar when the screw K⁶ is in its most forward position.

The screw K⁶ at the forward end of the bar K forms an abutment, against which the force of the crank or eccentric G⁵, transmitted 70 through the rod K⁴, operates. Therefore by adjusting this screw K⁶ longitudinally in the bar K the forward motion imparted to the bar K may be varied. As, however, the rearward motion of the bar K is produced solely by the 75 spring K³, the bar K will be always moved backward to the same position, no matter how much its forward movement may have been restricted by the adjustment of the screw K⁶.

I am aware that it is old to construct feed 80 mechanisms in which the extent of the movement has been limited, and I do not claim, broadly, such limitation; but what I have invented is a new combination of parts for effecting the limitation of the forward movement of 85 the feed-bar, while the limit of its backward movement remains always the same.

What I claim as my invention, and desire to secure by Letters Patent, is—

1. In a sewing-machine, the combination of 90 a bar for effecting the feed of the work, a support on which the bar is hung near its forward end, a shaft, an eccentric or crank on said shaft, a rod connected to the eccentric or crank, fitted loosely into a socket in the end 95 of said feed-bar and serving to impart motion to the bar in one direction, and a spring within the said feed-bar for imparting motion in the reverse direction, substantially as specified.

2. In a sewing-machine, the combination of 100 a bar for effecting the feed of the work, a support on which the bar is hung near its forward end, a shaft, a crank or eccentric on said shaft, a rod connected to the crank or eccentric, fitted loosely into a socket in the end of 105 the feed-bar and serving to impart motion to the bar in one direction, an adjustable abutment with which the bar is provided and against which the rod exerts its force, and a spring within the feed-bar for imparting motion to the bar in the reverse direction, substantially as specified.
